SHOE STRETCHING DEVICE

Filed Aug. 4, 1923

INVENTOR
A. H. Anderson
By Howard P. Denison
ATTORNEY

UNITED STATES PATENT OFFICE.

ADELBERT H. ANDERSON, OF CANASTOTA, NEW YORK.

SHOE-STRETCHING DEVICE.

Application filed August 4, 1923. Serial No. 655,640.

To all whom it may concern:

Be it known that I, ADELBERT H. ANDERSON, a citizen of the United States of America, of Canastota, in the county of 5 Madison, in the State of New York, have invented new and useful Improvements in Shoe-Stretching Devices, of which the following, taken in connection with the accompanying drawings, is a full, clear, and exact 10 description.

This invention relates to a device for stretching and smoothing the "counter" and cross seams of the "uppers" of shoes and analogous articles of wearing apparel to 15 cause the same to fit more comfortably upon the foot of the wearer.

It frequently happens that shoes which are carried in stock for greater or less period of time become more or less deformed, 20 particularly along the upper marginal edge of the "counter", around the rear of the heel and at the cross seams and toe box of the "upper", and at other times, even though the shoes of a pair may be perfect 25 in form and well matched so that even if one shoe may properly fit the corresponding foot of the wearer, the other foot may be of slightly different conformation than its corresponding shoe so that the wearing of the 30 latter might produce more or less irritation of the foot particularly at the points named, and the main object of my present invention 35 is to provide a simple and comparatively inexpensive implement capable of being used by the seller or user for reforming such portions of the shoe as may be required to adjust to be comfortable upon the foot of the wearer.

In other words, I have sought to render 40 the same implement useful for application to either the "counter" or to the various parts including the cross seams and caps of the "upper" of the shoe, and at the same time to avoid any excessive pressure or force 45 which would overstrain the leather or seams during the stretching or smoothing operations and to determine such pressure or force solely by the sense of feeling.

Other objects and uses relating to specific 50 parts of the device will be brought out in the following description.

In the drawings:

Figure 1 is a perspective view of a shoe stretching device embodying the various features of my invention.

55

Figure 2 is a longitudinal sectional view of the same taken on line 2—2, Figure 1.

Figures 3 and 4 are transverse sectional views taken on lines 3—3, and 4—4, Figure 1.

60

Figure 5 is a sectional view of a shoe showing the larger end of the stretching device in position for stretching and smoothing the upper marginal edge of the "counter", the dotted lines indicating the 65 smaller end of the same device in operative position for stretching and smoothing the cross seams and toe caps of the "upper".

This device is preferably made of hard wood such as maple although it may be 70 made of any suitable material and consists of an elongated bar of greater length than the length of the shoe so that when one end is inserted in the toe, the other end will extend some distance beyond the heel to serve 75 as a handle by which the device may be rocked by hand about its longitudinal axis or when the last named end is inserted into the heel end of the shoe and its opposite end may project some distance above the tip of 80 the shoe to also serve as a handle by which the device may be rotated about its longitudinal axis.

A certain portion of the length of one 85 end as —1—, of the device somewhat greater than the height of the "counter" as —a—, of the shoe —A—, is oblong in cross section with its greatest width somewhat less than the transverse width of the portion of the shoe which receives the heel of the user and 90 therefore of less width than the opening in the top of the shoe which receives the ankle thus permitting that end of the device to be readily inserted into the opening of the shoe adjacent the "counter" —a— as shown in 95 Figure 5, whereupon the shoe may be taken in one hand and the upper end of the device in the other hand and said device rotated about its longitudinal axis with sufficient manual force or pressure against the upper 100 marginal edge of the "counter" to stretch and smooth the same as may be required to

render the wearing of the shoe more comfortable at that point.

- The outer or lower end of the enlarged oblong portion —1— is tapered or rounding 5 at —2— to enable it to conform more closely to the interior contour of the portion of the shoe at the base of the "counter" —a— and to also form a smooth bearing on the upper portion of the heel to prevent mutilation of 10 the lining of the shoe and also to facilitate the rotation of the device around and against the upper marginal edge of the "counter" with the pressure required to produce the desired stretching and smoothing.
- 15 The opposite end as —3—, of the device is reduced in cross sectional size, but is also oblong or elliptical in cross section and of less size than the interior cross sectional size of the toe of the shoe into which it is 20 adapted to be inserted under forward end-wise pressure by hand, and then rotated about its longitudinal axis to produce the desired stretching and smoothing of the transverse seams or cap as shown, of the 25 "upper" —b'—.
- The elliptical portion —3— of the device continues from the small end some distance toward the larger end a distance equal to or slightly greater than the distance from the 30 toe cap to the opening in the top of the shoe to permit all parts thereof to be utilized in stretching and smoothing the cross seams and toe cap of the "upper", the portions between the enlarged end —1— and smaller elliptical end being gradually freer in one direction or tapered in the opposite direction so that the outer surfaces named, 35 gradually merge with the larger and smaller ends.
- 40 The longitudinal corners of the oblong end —1— are also rounding in cross section, and gradually merge into the elliptical portion —3— of the small end so as to prevent abrasion or mutilation of the lining or leather of the shoe when the device is rotated about its longitudinal axis in the act 45 of stretching the different parts of the shoe.

For a similar reason, the corners of the outer end of the small elliptical portion

—3— are also rounded and serve as bearings against the inner sole of the shoe when the smaller end is inserted in the toe thereof, and the device rotated for stretching and smoothing the seams and toe caps.

When the device is used for stretching 55 and smoothing the "counter", the larger end —1— is inserted through the opening in the top of the shoe with its lower end resting upon the heel of said shoe, the upper or small end being then used as a handle 60 whereby the larger end may be pressed firmly against the "counter" and rotated about its longitudinal axis to effect the desired stretching and smoothing of the 65 "counter".

In order to stretch and smooth the cross seams and its cap of the "upper", the smaller elliptical end of the device is inserted through the opening in the top of the shoe until tightly wedged between the 70 upper side of the upper and insole whereupon the larger end may be used as a handle by which the device is pressed forwardly and simultaneously rotated about its longitudinal axis to produce the desired stretch 75 and smoothing of the cross seams and toe cap.

What I claim is:

A shoe stretching device consisting of an elongated bar having one end relatively 80 larger than its other end, the larger end being substantially rectangular in cross section and the smaller end substantially elliptical in cross section, the length of the larger rectangular end being greater than the 85 depth of the counter of a shoe for stretching all portions of said counter by a rotary pressing motion of said rectangular portion against the inside of the counter, the smaller elliptical end being adapted to be 90 used to stretch the toe of the shoe.

In witness whereof I have hereunto set my hand this 25th day of July, 1923.

ADELBERT H. ANDERSON.
